(57) **CLAIM**

The ornamental design for a bra for nursing and pumping, as shown and described.

DESCRIPTION

FIG. 1 is a front, right, top perspective view of a bra for nursing and pumping in the first usage state, showing my new design;

FIG. 2 is a rear, left, bottom perspective view thereof;

FIG. 3 is a rear, left, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 1;

FIG. 11 is an enlarged view of detail 11 in FIG. 1;

FIG. 12 is an enlarged view of detail 12 in FIG. 2;

FIG. 13 is an enlarged view of detail 13 in FIG. 3;

FIG. 14 is an enlarged view of detail 14 in FIG. 3;

FIG. 15 is an enlarged view of detail 15 in FIG. 5;

FIG. 16 is an enlarged view of detail 16 in FIG. 8;

FIG. 17 is a front, right, top perspective view of the bra for nursing and pumping in the second usage state;

FIG. 18 is a front, right, top perspective view of the bra for nursing and pumping in the third usage state;

FIG. 19 is a front, right, top perspective view of the bra for nursing and pumping in the fourth usage state; and,

FIG. 20 is a front, right, top perspective view of the bra for nursing and pumping in the fifth usage state.

The dash-dot-dash broken lines are for notating enlarged views and form no part of the claimed design.

The dashed broken lines in the FIG. 18 are for the purposes of indicating the usage environment of the bra for nursing and pumping and form no part of the claimed design.

1 Claim, 20 Drawing Sheets
